Primary Examiner — John Windmuller*Assistant Examiner* — John R Yeh(74) *Attorney, Agent, or Firm* — Scherrer Patent & Trademark Law, P.C.; Stephen T. Scherrer; Monique A. Morneau(57) **CLAIM**

I claim the ornamental design for a display stand clamp, as shown and described.

DESCRIPTION

FIG. 1 is a perspective view of my design for a display stand clamp;

FIG. 2 is a top view thereof;

FIG. 3 is a bottom view thereof;

FIG. 4 is a left side view thereof;

FIG. 5 is a right side view thereof;

FIG. 6 is a front view thereof;

FIG. 7 is a rear view thereof;

FIG. 8 is a rear perspective view of the display stand clamp shown in the environment of its intended use thereof; and, FIG. 9 is a front view of the display stand clamp shown in the environment of its intended use thereof.

The broken lines are included to illustrate environment of the display stand clamp and form no part of the claimed design.

1 Claim, 5 Drawing Sheets(56)
